PNEUMATIC AMUSEMENT MACHINE GUN

Charles A. Feltman, Brooklyn, N. Y.

Application May 26, 1941, Serial No. 395,169

4 Claims. (Cl. 124—11)

My invention relates to pneumatic amusement machine guns and has particular reference to machine guns for use in shooting galleries.

My invention has for its object to provide a machine gun of a simple and inexpensive construction which can be used for a continuous projection of bullets from its magazine by compressed air until the magazine is exhausted, the starting and stopping of the shooting being manually controlled by a suitable trigger.

Another object of my invention is to provide an automatic means for controlling the rate of the charge of the balls through the barrel and for admitting the air into the barrel only at such moments when a ball is placed into the breech of the barrel. For this purpose I provide a rotary distributor operated by an electric motor.

In a modified construction I employ a cam operated plunger for delivering balls, one at a time, from the magazine into the barrel of the gun, this construction being an improvement on a disclosure in my Patent No. 2,238,384.

In another embodiment of my invention I provide a reciprocating air motor for operating a plunger which delivers balls from the magazine into the barrel, the gun being sufficiently light so that it can be fired from the shoulder without a tripod.

For convenience in handling the gun, I mount the same on a swivel supported on a permanent stand, stops being provided to limit the rotation of the gun in the vertical and horizontal planes.

My invention is more fully described in the accompanying specification and drawings, in which:

Fig. 1 is a fractional sectional elevational view of my machine gun;

Fig. 2 is an end view of the same;

Fig. 3 is an elevational view of the same;

Fig. 4 is a fractional sectional elevational view 40 of a modification representing a shoulder type submachine gun;

Fig. 5 is a side view of a firing mechanism;

Fig. 6 is an end view of the same;

Fig. 7 is a sectional detail view of a noise producing device;

Fig. 8 is an elevational view of the submachine gun on a smaller scale.

My machine gun consists of a block 84 having transverse holes 85 and 86 for a magazine pipe 87 fitted at one end into the front portion of the hole 85 and a barrel 7 fitted into the front portion of the hole 86. The magazine pipe is bent upon itself, the other end being fitted into a hole 88. Air supply pipe 89 is fitted into the rear end

5 of the hole 86, the other end of the pipe 88 extending from a control valve 59 for compressed air delivered by a flexible pipe 99. A reduction valve 91 extends from the valve 59 and is connected with an air supply pipe 92 for the magazine pipe 87, the pipe 92 being fitted into the rear portion of the hole 85. A hole 93 is drilled in the block 84 at a small angle to the hole 85 for delivering balls 11 into the magazine pipe through 10 a nipple 94. A valve 95 has a sufficiently large opening 96 for admitting the balls into the magazine pipe when it is open. This valve, when closed, seals the magazine pipe from the outside air.

15 The block 84 has a bore 97 for a cylindrical distributor or plunger 98. The latter has an extension 100 sliding in a plug 100' fitted in a bore 101 in a push rod 99. A spring 102 acts on a head 103 of the extension 100, keeping the plunger 98 and push rod apart. The push rod is of a larger diameter than the plunger 98, sliding in a larger bore 99' forming a shoulder 100' for a spring 109 whose other end rests against the upper end of the push rod. The spring 102 is sufficiently 20 strong to operate the cylinder 98 and serves only to soften the blows of the push rod against the cylinder and to compensate for any errors in the adjustment of the operative positions of the cylinder 98. The outer end of the push rod 99 has a roller 104 engaged by a cam 105 operated by a motor 18. The push rod 99 is locked in its upper or inoperative position by a yoke 106 engaging a notch 107 on the rod, the yoke being connected with a rod 108 extending from a push button 70 25 on the end of a valve rod 71. The push rod is released for operation when the yoke is moved out of the notch 107 by depressing the push button 70, thereby opening the valve and admitting compressed air into the gun.

30 The cylinder 98 has a depression 110 at one side for receiving one ball from the magazine when the cylinder is in its upper position, as shown in Fig. 1. The exact position of the cylinder is determined by a pin 111 engaging the lower edge of a slot 112 in the plunger. A light spring 113 presses the pin 111 against the cylinder. The latter has a hole for the pin extending into the depression or recess 110, so that the end of the pin extends into the recess, preventing movement of the cylinder. The pin, however, is pushed back when there are balls in the magazine under air pressure from the pipe 92. The low 35 position of the cylinder is determined by the upper edge of the slot 112 engaging the pin 111. The depression 110 with the ball 11 is placed

opposite the rear end of the barrel when the cylinder is moved downward, to be ejected by the air pressure, acting through the pipe 89 and hole in the plunger. The cylinder 98 is prevented from rotation by a set screw 113, engaging a flat side 114 of the cylinder.

Still another modification is shown in Figs. 13 to 17 inclusive, representing a portable submachine gun or Tommy gun. It has a main block 115, drilled at 116 for a barrel 7. A magazine pipe 117 is fitted into a bushing 118 inserted into a corresponding bore in the other side of the block. A distributing cylinder or plunger 119 slides in a bushing 120 fitted in a bore 121. The cylinder 119 has a transverse hole 122 of the same diameter as the balls 11 which it receives from the bushing 118. A slot 123, engaged by a set screw 124, determines the exact position of the hole 122 opposite the magazine bushing 118 in the lower position of the cylinder, and opposite the barrel 7 in the upper position of the cylinder. The ball is ejected through the barrel in the latter position of the cylinder 119 by the compressed air admitted through an air pipe 125 and duct 126. The air pipe receives compressed air through a duct 127 in the upper block 115 and a pipe 127' in the lower block 128 connected with a flexible supply pipe 90. A valve 129 controls the air supply to the duct 126. The valve is normally maintained closed by a spring 131 engaging a button 132 on a stem 130. The valve is opened by a trigger 133 (Fig. 17).

The pipes 117 and 125 are fitted at the rear into a block 134 and are connected together by a duct 135. A bore 136 extends from the pipe 117 to the rear of the block and has an enlarged opening for inserting balls into the magazine. The bore 136 is normally closed by a plunger 137 sliding in a transverse bore 138 and extending outside the block. A spring 139, resting against a head 140, keeps the plunger in a withdrawn position. The plunger can be pushed up by pressing on the head 140, thereby bringing a hole 141 in line with the bore 136 when it is desired to charge the magazine pipe with the balls. The movements of the plunger 137 are limited by a set screw 142 engaging a slot 143 in the plunger.

The distributing cylinder 119 is operated by an air motor consisting of a free plunger 144 sliding in a bore 145 in the lower block 128. The plunger normally rests against a screw plug 145 under pressure of a spring 146 engaging a head 147 on the cylinder 119. Elastic connection between the cylinder 119 and plunger 144 is provided by a spring 148 in a bore 149 engaging an extension 150 on the lower end of the cylinder 119.

The plunger 144 is raised by the compressed air admitted to its lower end by a duct 151 extending from the duct 126 through a rotary valve 152. The valve extends to the outside of the block and has an arm 153 movable between pins 154 and 155. It is normally pressed against the pin 154 by a spring 156 attached at the other end to a bar 157, the valve being then open. The bar 157 is attached to a pin 158 extending from the plunger 144 through an elongated slot 159 in the wall of the block 128.

The valve 152 being normally open, the compressed air raises the plunger 144 as soon as the trigger valve 129 is opened. The plunger brings a ball 11 to the rear end of the barrel, and the ball is fired through the barrel by the air pressure through the duct 126. The bar 157, how-

ever, passes to the other side of the valve 152, so that the spring 156 pulls the arm 153 into the upper position shown in dotted lines in Fig. 14, thereby closing the valve. The spring 146 moves the cylinder 119 down, bringing also down the plunger 144. The arm 153 is again moved down against the pin 154, opening the valve. The operation continues as long as the trigger valve 129 is open, the plunger and the cylinder reciprocating at a high rate of speed until all the balls in the magazine pipe 117 are fired. The valve 152 has an exhaust opening 152' at right angles to the intake opening, the exhaust air passing through a duct 151, and through a hole 154' to the outside, a screw 144' controlling the exhaust opening thereby controlling the speed of the operation.

The valve 152 has an exhaust opening 152' at right angles to the intake opening, the exhaust air passing through a duct 151' and through a hole 154' to the outside, a screw 144' controlling the exhaust opening, thereby controlling the speed of the operation.

In order to prevent operation of the plungers when there are no more balls in the magazine, a safety device is provided consisting of a bar 155 rotating on a pin 156 in a slot 157 in the bushing 118. The bar has a flat upper side engaged by the flat side of a shaft 158 extending to the outside of the block 115. An arm 159 is attached to the shaft 158 and is pivoted at 160 to one end of a link 161, the other end being pivoted at 162 to a lever 163. The latter rotates on a pin 164 and is pulled downward by a spring 165 extending from the end of a cam arm 166 pivoted at 167 on the block 128. The arm 166 is normally turned to the left, maintaining the spring 165 under light tension, so that the bar 155 is readily deflected upward by the balls, moving in the bushing 118, turning the shaft 158 and raising the lever 163. The spring 165 is tightened when the plunger 144 is moved upward, the pin 156 engaging the cam portion 168 of the arm 166 and moving it to the right. In this position of the arm 166, the lever 163 is moved downward if there are no more balls in the magazine pipe to raise the bar 155, so that the sharp end of the arm 159 is caught by a hook 169 on the end of the lever 163, retaining the latter in this position with the valve 152 closed. It will be opened again, however, when the magazine pipe 117 is filled with the balls, raising the bar 155.

The cylinder 119 is prevented from rotation by a set screw 173, engaging a corresponding flat side of the cylinder.

A noise producing device 174 is attached to the muzzle of the barrel 7, the device consisting of a tube of a larger diameter than the bore, the tube having in the middle a diaphragm 176 with an opening 177 of the same diameter as the bore of the barrel 7. The balls, passing through the diaphragm produce a sharp explosive noise.

The gun may be enclosed in a suitable casing 178 as shown in Fig. 17, with fins 179 for the barrel and handles 180, 181, mounted for rotation on a base 182.

It is understood that my pneumatic amusement machine gun may be further modified without departing from the spirit of the invention, as set forth in the appended claims.

I claim as my invention:

1. A pneumatic machine gun comprising a block, a pipe extending from the block forming a magazine for balls, a barrel extending from the block for firing the balls, the block having chan-

nels in communication with the pipe and with the barrel, a cylindrical member slidably fitted in the block for movement in the plane of the channels and provided with a recess for receiving a ball from the magazine, an air motor operatively connected with the cylindrical member, a valve in the block for admitting compressed air to the air motor for reciprocating the cylindrical member, the cylindrical member being adapted to receive a ball from the magazine into the recess and to transfer the ball to the back of the barrel, the ball being adapted to be projected through the barrel by the compressed air, and means to render the air valve inoperative when no more balls are left in the magazine.

2. A pneumatic machine gun comprising a block, a pipe extending from the block forming a magazine for balls, a barrel extending from the block for firing the balls, the block having channels in communication with the pipe and with the barrel, a cylindrical member slidably fitted in the block for movement in the plane of the channels and provided with a recess for receiving a ball from the magazine, a plunger slidably supported at the block engaging the cylindrical member, a valve for admitting compressed air to the outer end of the plunger for moving the plunger against the cylindrical member, thereby placing the recess in position for receiving a ball from the magazine, means to release the air from the plunger, means to return the cylindrical member into a firing position with the ball in the recess opposite the barrel, and means controlled by the movement of the balls in the magazine for rendering the valve operative.

3. A pneumatic machine gun comprising a block, a pipe extending from the block forming a magazine for balls, a barrel extending from the block for firing the balls, the block having channels in communication with the pipe and with the barrel, an elongated member slidably fitted in the block for movement in the plane of

the channels and provided with a recess for receiving a ball from the magazine, means to move the member by compressed air into a position for receiving a ball from the magazine into the recess, yieldable means for returning the member into a firing position with the ball opposite the barrel, the ball being then adapted to be projected through the barrel by the compressed air, and a valve to separately control the air pressure from the magazine for the member and for firing the ball.

4. A pneumatic machine gun comprising a block, a pipe extending from the block forming a magazine for balls, a barrel extending from the block for firing the balls, the block having channels in communication with the pipe and with the barrel, an elongated member slidably fitted in the block for movement in the plane of the channels and provided with a recess for receiving a ball from the magazine, a plunger slidably fitted in a tubular chamber in the block operatively connected with the member, a valve for admitting compressed air into the chamber at the end of the plunger for moving the plunger against the elongated member so as to bring the recess in alignment with the magazine for receiving a ball, means to control the valve by the movement of the plunger for releasing the air at the completion of the movement of the plunger, means to return the elongated member into a firing position with the ball opposite the barrel and in alignment with an opening in the block for admitting the compressed air into the barrel, thereby firing the ball, a latch movably supported on the block, and a bar connected to the latch extending into the magazine channel, the latch being adapted to engage the valve, thereby rendering the plunger inoperative, the latch being adapted to be rendered inoperative when the bar is raised by the balls in the magazine channel.

CHARLES A. FELTMAN.
